US0D1109027S

(12) **United States Design Patent** (10) **Patent No.:** **US D1,109,027 S**
(45) **Date of Patent:** **** Jan. 13, 2026**

(54) **RADIATOR COVER**

(71) Applicant: **Harley-Davidson Motor Company, Inc.**, Milwaukee, WI (US)

(72) Inventors: **Mark Daniels**, Mequon, WI (US); **Frank Savage**, Fox Point, WI (US); **Brad Richards**, Grafton, WI (US); **Scott Matthews**, Franklin, WI (US); **Alexander John Bozmoski**, Brookfield, WI (US); **Jeffrey Smith**, Waukesha, WI (US); **Terry Rumpel**, West Bend, WI (US); **Michael Case**, Hartland, WI (US); **Kyle Wick**, Menomonee Falls, WI (US); **Michael Carlin**, Sussex, WI (US); **Matthew Mueller**, Wauwatosa, WI (US)

(73) Assignee: **Harley-Davidson Motor Company, Inc.**, Milwaukee, WI (US)

(**) Term: **15 Years**

(21) Appl. No.: **30/007,151**

(22) Filed: **Jun. 6, 2025**

Related U.S. Application Data

(60) Continuation of application No. 29/915,904, filed on Nov. 6, 2023, now Pat. No. Des. 1,085,488, which is a division of application No. 29/813,942, filed on Nov. 2, 2021, now Pat. No. Des. 1,010,518, which is a division of application No. 29/726,407, filed on Mar. 3, 2020, now Pat. No. Des. 937,746, which is a division of application No. 29/658,284, filed on Jul. 30, 2018, now Pat. No. Des. 880,364.

(74) *Attorney, Agent, or Firm* — FOLEY & LARDNER LLP

(57) **CLAIM**

The ornamental design for a radiator cover as shown and described.

DESCRIPTION

FIG. 1 is a bottom, front, left perspective view of a radiator cover embodying our new design;

FIG. 2 is a bottom, rear, left perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the drawings illustrate portions of the radiator cover that form no part of the claimed design.

1 Claim, 8 Drawing Sheets
